CLAIM

We claim the ornamental design for a packaging blank, as shown and described.

DESCRIPTION

FIG. 1 is a perspective view of a packaging blank showing a first embodiment of our new design;

FIG. 2 is a top plan view thereof, the bottom plan view being a mirror image thereof;

FIG. 3 is a right side elevation view thereof;

FIG. 4 is a left side elevation view thereof;

FIG. 5 is a front elevation view thereof;

FIG. 6 is a rear elevation view thereof;

FIG. 7 is a perspective view of a packaging blank showing a second embodiment of our new design;

FIG. 8 is a top plan view thereof;

FIG. 9 is a bottom plan view thereof;

FIG. 10 is a right side elevation view thereof;

FIG. 11 is a left side elevation view thereof;

FIG. 12 is a front elevation view thereof; and,

FIG. 13 is a rear elevation view thereof.

The dotted lines represent fold lines and form part of the claimed design. The dashed lines depict portions of the packaging blank that form no part of the claimed design. The shade lines are used to show that the surface is substantially planar and are not to be interpreted as surface ornamentation.

The long dash-short dash-short dash-long dash broken lines along one of the end planes of the packaging blank in FIGS. 7-11 depict break lines. The break lines and the areas between the break lines form no part of the claimed design.
